UNITED STATES PATENT OFFICE.

JOEL BLOMSTER AND JOSEPH SCHABEN, OF ALGONA, IOWA, ASSIGNEES TO JOSEPH SCHABEN, OF ALGONA, IOWA.

SPARK-PLUG.

1,354,945.

Specification of Letters Patent.

Patented Oct. 5, 1920.

Application filed June 23, 1919. Serial No. 306,252.

To all whom it may concern:

Be it known that we, JOEL BLOMSTER and JOSEPH SCHABEN, citizens of the United States, residing at Algona, in the county of Kossuth and State of Iowa, have invented 5 certain new and useful Improvements in Spark-Plugs; and we do hereby declare the following to be a full, clear, and exact description of the invention, such as will enable others skilled in the art to which it 10 appertains to make and use the same.

The present invention relates to spark plugs, and has for its object the provision of novel and improved coöperating electrodes to provide an effective spark under 15 all conditions, and so arranged and formed that carbon deposits will be blown or cleaned from the electrodes.

A further object is the provision of a 20 spark plug so formed as to reduce to a minimum the liability for oil working upwardly into the plug and fouling same.

With the foregoing and other objects in 25 view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawing, wherein:

Figure 1 is a side elevation of the spark plug embodying the improvements, portions being broken away as shown in section.

Fig. 2 is an inner end view of the plug.

Fig. 3 is a side elevation of the inner end portion of the plug looking at right angles 40 to the line of view in Fig. 1.

Fig. 4 is a view, partly in elevation and partly in longitudinal section, showing a modification.

The plug embodies according to the usual 45 practice a tubular shell or body 1 of metal, and an insulator 2 secured within said shell, and provided at its outer end with a binding post 3 for the connection of the wire or electrical conductor.

In carrying out the invention, the inner 50 electrode 4, comprising a rod of metal, extends from the inner end of the insulator 2 through the inner end of the shell 1 beyond same, and the end of the electrode 4 is preferably tapered as at 5, and is provided with

a recess or hole 6 therein, whereby the annular wall formed by the recess or hole, will be comparatively thin so as to become heated and therefore cause the carbon deposit thereon to crumble and fall off. 60

The inner end portion of the shell 1, is thickened as at 7, so as to reduce the opening at the inner end of the shell, and therefore reduce to a minimum the liability of oil working up within the shell, and this 65 will lessen the possibility of the plug becoming fouled with oil. This thickening of the end of the plug or contraction of the opening is limited to the end of the shell and the opening or bore of the plug is 70 larger in diameter above the inner end of the shell, as seen in Fig. 4.

The outer electrode 8 is of arcuate cross section or concaved longitudinally, and extends obliquely from the inner end of the 75 shell 1 at one side thereof to the end of the electrode 4, so that said electrodes converge toward one another with their active ends close together to provide the spark gap. The basal end of the electrode 8 has a shank 80 9 to be secured within a hole or aperture 10 formed in the thickened end of the shell, thereby making the electrical connection between the electrode 8 and shell 1. The electrode 8 being of curved or concaved cross 85 section extends partially around the end of the electrodes 4, as seen in Fig. 2, thus providing an arcuate spark gap across which the sparks can jump at various points, to assure of an effective spark under all conditions. 90 Furthermore, by the arrangement of the electrode 8, it extends partially across the open end of the shell, and converges toward the electrode 4, so that when the explosion occurs, the burning gases in being expelled 95 from the chamber of the shell will be caught by the electrode 8 and carried through the spark gap between the two electrodes so as to blow out the carbon deposits therefrom.

The electrodes 8 as well as the end of the electrode 4 are thin so as to be heated for drying and crumbling the carbon, and the electrode 8 being of scoop shape will catch the expanding gases which pass from within the shell, and thus direct such gases to the restricted spark gap for effectively blowing the carbon from the adjacent sides of the electrodes. 105

The expanding gases in passing from the shell are caught within the electrode 8, and 110

said electrode being of scoop or channel-shape will retain the gases therein directed away from the shell and will conduct such gases with considerable force through the 5 spark gap. The space between the electrode 4 and shell 1 opposite to the electrode 8 is not encumbered so that there is free circulation into and out of the shell, and the electrode 8 being arranged to catch a sufficient 10 amount of the gas flowing from the shell to create the concentrated flow of gas through the spark gap for keeping the electrodes clean.

In Fig. 4, a modification is shown, wherein 15 the electrode 8' has a shank 9' integral with the end of a sleeve 11 fitted within the shell and provided with a flange 12 at its opposite end clamped against the shoulder 15 within the shell upon which insulator 2 is clamped. 20 This sleeve 11 can be readily inserted into the shell before the insulator 2 is inserted, and is therefore held in place by the same means which secures the insulator within the shell, instead of securing the outer electrode 25 to the inner end of the shell by independent means as shown in Fig. 1.

Having thus described the invention, what is claimed as new is:—

1. A spark plug embodying a shell having 30 a shoulder therein, an insulator secured

within said shell, a sleeve fitted in said shell and having a flange at its outer end clamped between said shoulder and insulator, an inner electrode extending through said insulator and beyond the inner end of the shell, 35 and an outer electrode extending from the other end of said sleeve obliquely toward the inner electrode and converging to the end thereof, said outer electrode being concaved transversely and extending partially 40 around said end of the inner electrode.

2. A spark plug embodying a shell, an inner electrode extending from within the shell beyond the inner end thereof, the end of the 45 said electrode being hollow, and an outer electrode extending obliquely from the inner end of the shell at one side and converging to the end of the inner electrode, said outer electrode being concaved transversely and extending partially around said hollow end 50 of the inner electrode.

In testimony whereof we have signed our names to this specification in the presence of two subscribing witnesses.
